UNITED STATES PATENT OFFICE.

THOMAS H. NIELSEN, OF WYOMING, DELAWARE.

RADIATOR-DOME FOR PIPELESS HEATERS.

1,280,817.

Specification of Letters Patent.

Patented Oct. 8, 1918.

Application filed May 13, 1918. Serial No. 234,230.

To all whom it may concern:

Be it known that I, THOMAS H. NIELSEN, a citizen of the United States, residing at Wyoming, in the county of Kent and State 5 of Delaware, have invented certain new and useful Improvements in Radiator-Domes for Pipeless Heaters; and do hereby declare the following to be a full, clear, and exact description of the invention, such as will enable others skilled in the art to which it appertains to make and use the same, reference being had to the accompanying drawings, and to the letters and figures of reference marked thereon, which form a part of 10 this specification.

This invention relates to new and useful improvements in apparatus for increasing the radiating surface of pipeless heaters and consists of a simple and efficient device of 20 this nature having various details of construction, combinations and arrangements of parts which will be hereinafter fully described, shown in the accompanying drawings and then specifically defined in the appended claim.

My invention is illustrated in the accompanying drawings which, with the letters of reference marked thereon, form a part of this application and in which:

30 Figure 1 is a view in elevation of a pipeless heater in connection with which my invention is illustrated, parts being shown in vertical section.

Fig. 2 is a top plan view of the circular radiating drum shown as partly broken away and in section with the auxiliary drum omitted.

Fig. 3 is a vertical sectional view on line 3—3 of Fig. 2, including the auxiliary drum.

40 Reference now being had to the details of the drawings by letters:

A designates the usual pipeless heater having the double walls B and C spaced apart forming the heating chambers D and 45 E, having respectively exit passageways D' and E' to the register F in the floor H. The upper portion of the furnace, designated by letter I, is provided with an annular radiating drum O, having a diagonal 50 partition O' formed therein, as shown in Fig. 2 of the drawings, and L is a clean-out

pipe communicating with the chamber O, and L' a smoke pipe leading from the latter.

As shown in Fig. 3 of the drawings, the furnace I communicates through the passageway I' with the interior of the auxiliary heating drum N, having a partition N' rising therein and terminating a short distance below the top of said auxiliary heating drum, causing the smoke to make a circuitous passageway through the latter. The auxiliary heating drum has an exit passageway Q leading into the annular radiating drum. A damper P is mounted in the radiating drum leading from the passageway I', 60 and is pivotally mounted in the walls thereof, and has a crank end P' pivotally connected to the operating rod T.

By the provision of an auxiliary heating drum made in accordance with my invention, it will be noted that the radiating surface of the furnace is appreciably increased by causing the smoke from the furnace to pass up into the auxiliary heating drum above the partition N', thence down through the opening Q, afterward passing through 70 the annular radiating drum and making exit in the pipe L'. All of the products of combustion are caused to take this course when the damper is in a closed position, as shown 80 in Fig. 2 in dotted lines and in elevation in Fig. 3. When the damper is thrown to a different angle part of the products of combustion from the furnace may pass through into the radiating drum without going 85 through the auxiliary heating drum.

By the provision of an auxiliary heating drum such as described it will be noted that an appreciable amount of heat which otherwise would be lost, is utilized for heating 90 the air before making exit through the register. While my auxiliary heating drum is adapted for heaters in general, it is especially adapted for the type of heater known as the pipeless heater, as illustrated in the 95 drawings.

What I claim to be new is:

In combination with a furnace, having an annular radiating drum provided with a partition therein, a smoke pipe leading from 100 the drum, an auxiliary heating drum mounted upon the annular radiating drum, and

having an opening communicating with the latter above the furnace, and a passageway leading from the auxiliary heating drum to the smoke pipe, and a damper in said passageway to cause the products of combustion to pass through the auxiliary heating drum and make exit into the smoke pipe.

Copies of this patent may be obtained for five cents each, by addressing the "Commissioner of Patents, Washington, D. C."

In testimony whereof I hereunto affix my signature in presence of two witnesses.

THOMAS H. NIELSEN.

Witnesses:

A. L. HOUGH,
FRANKLIN H. HOUGH.
